UNITED STATES PATENT OFFICE.

WILLIAM J. WRIGHT, OF PITTSBURG, PENNSYLVANIA, ASSIGNOR OF THREE-SIXTEENTHS TO J. W. LEE AND FRED J. GALLOWAY, OF PITTSBURG, PENNSYLVANIA.

EXPLOSIVE-ENGINE.

SPECIFICATION forming part of Letters Patent No. 739,050, dated September 15, 1903.

Application filed February 21, 1902. Serial No. 95,097. (No model.)

To all whom it may concern:

Be it known that I, WILLIAM J. WRIGHT, of Pittsburgh, in the county of Allegheny and State of Pennsylvania, have invented certain new and useful Improvements in Explosive-Engines, of which the following is a specification.

My present invention seeks to provide a new construction of explosive-engine in which the several parts have a special coöperative arrangement, whereby the expansive force of the burned mixture can be utilized for aiding in running the machine, and the use of pump-cylinders coupled with the explosive-cylinder is dispensed with; and the said invention also seeks to provide a simple and effective means for creating a vacuum for drawing off the burned mixture after its expansive force is utilized and for drawing a new charge into the explosion-chamber.

With other objects in view, which will hereinafter be explained, my invention consists in the peculiar combination and novel correlation of parts, all of which will hereinafter be fully explained and particularly pointed out in the appended claims, reference being had to the accompanying drawings, in which—

Figure 1 is a vertical longitudinal section of the pump-cylinder, the explosion or working cylinder, and the compound operating cylinder, with the several valve and feed connections, hereinafter specially referred to, the crank-shaft and valve-gear devices being also shown. Fig. 2 is a horizontal section taken practically on the line 2 2 of Fig. 1. Fig. 3 is a diagram illustrating the correlative arrangement of the pump, the working and compound cylinders, their pistons, and the connections for joining said pistons with the crank disk and shaft. Fig. 4 is a detail sectional view illustrating a governor mechanism for controlling the working-agent feed to the working cylinder.

In the accompanying drawings I have illustrated a mechanism embodying my invention; but I desire it understood the detailed arrangement of the several parts may be modified or varied to suit the particular character of work for which it may be desired to utilize my improved type of engine.

In the practical application of my invention I employ a working (explosive) cylinder A, mounted upon a suitable bed or frame B, having the usual slideway for the cross-head C, with which the rod D' of the working piston connects and which in turn connects with the crank member or wrist-pin E' of the crank-shaft E, mounted on the bed or frame B and provided with a band-pulley and balance-wheel in the usual manner.

In my present construction the cross-head joins with the crank or wrist-pin E' by a double bell-crank lever F, the two short arms f' f² of which project in opposite directions and the long arm f³ forwardly to engage the crank or wrist-pin E', as clearly shown in Fig. 1, by reference to which it will also be noticed the said lever F is fulcrumed on the cross-head by the pin f⁵, that lies in a horizontal plane with the crank-shaft and the axis of the working piston. The purpose of the two oppositely-extended members f' f² will be herein-after explained.

The working cylinder A has valved intakes a a', one at each end, and centrally it has two adjacent exhausts b b', as clearly shown in Fig. 1.

G designates a working-agent-feed pipe that communicates through the laterally-extending conveyer or pipe members g g with the valved intakes a a' to the cylinder A, and to provide for an economical and uniform feed of the working agent a governor mechanism, (indicated by H) geared with and controlled by crank-shaft E, is employed. As any ordinary type of governor mechanism can be utilized for coöperating with my present type of engine and as the governor mechanism *per se* forms no part of my present invention, a detailed description of said governor mechanism is deemed unnecessary. The intakes a a' have valves a² a³, adapted to open inward under ordinary feed-pressure and to close off the feed from that end of the working cylinder in which a charge is being compressed and exploded.

J designates what I term the "compound cylinder," which in the drawings is shown as located under the working cylinder, and the said cylinder J has an intake at each end,

(designated by j, j'), each regulated by a mechanically-controlled valve j^8 , normally held closed by a spring or equivalent means and adapted to be opened at predetermined times by the cams k, k' on a shaft K, geared with and controlled by the movement of the crank-shaft. The intakes j, j' of the cylinder J are connected with the exhausts b, b' of the working cylinder, the pipes j^3 , connecting the said 10 exhausts b, b' with the intakes j, j' , having a crossed relation, so the exhaust b' joins with the intake j and the exhaust b with the intake j' to provide for a proper uniform movement of the several operating-pistons, presently 15 referred to. The cylinder J is also provided at each end with an outlet j^5, j^6 , also normally closed by a valve j^8 , arranged to be mechanically opened at predetermined times by the cams l^2, l^3 on shaft L, also geared with 20 the crank-shaft, the intake and outlet controlling valve operating mechanisms for the cylinder J having such correlative action that the intake and outlet at one end of the cylinder will at times be opened in unison as 25 the intake and outlet at the other end of said cylinder remain closed, and vice versa.

M designates a condensing-coil that connects with the outlets j^5, j^6 of the cylinder J, and the said coil for effecting a quick cooling 30 and condensing of the residuum drawn from the cylinder J in the manner presently explained is held in a cooling-vat N, and its discharge end extends up and connects with the pump-cylinder O, (see Fig. 1,) which 35 operates to draw off all of the condensations of burned charges and also to create a vacuum for effecting a recharge of the working cylinder, as will presently more fully appear.

J^5 designates the piston for the compound 40 cylinder, the rod of which connects with the arm f^2 of the crank and cross-head engaged member F, and O^5 designates the pump-piston, the rod o^5 of which connects with the other arm, f' , and to steady the movement of 45 the two piston-rods they are slidably in brackets P P, made fast to and projected in opposite directions from the cross-head.

The working or explosive cylinder has igniting-tubes R and S of the usual construction 50 and arrangement, or, if desired, electric igniting means may be combined therewith in a manner well understood to those skilled in the art to which my present invention relates.

55 The manner in which my improved engine operates is best explained as follows, the several parts being in the position shown in Fig. 1 and assuming the working piston to have been traveling in the direction indicated by 60 the arrow z under the explosive force: Just as the working piston R reaches the position shown in Fig. 1 and uncovers the port b' the cam k will open the valve for the intake j and allow the exploded mixture to pass out from 65 the working cylinder through the port b' and j into the left-hand end of the cylinder J, it being understood that at this time the intake

a' is closed, as is also the valved port j^5 , it being further understood that the burnt mixture which passes from the working cylinder 70 to the cylinder J has not been completely expanded at this time, and therefore will cause the piston in the cylinder J to move forward a short distance in the direction of the arrow y , and thereby overcome the dead-center. 75 During this slight movement of the piston it will be understood that the working piston remains practically at rest and does not yet cover the port b' . As soon as the piston in the cylinder J has moved slightly forward in 80 the direction of the arrow y the cam l^2 will open the port j^5 and allow the pump O to withdraw the burnt mixture in the working cylinder and the cylinder J through the port b' , intake j , and port j^5 , and at the same time as 85 the burnt mixture is being withdrawn the new charge is drawn into the working cylinder through the valved intake a' , and by the time the new charge has entered the working cylinder the working piston will have re-covered the port b' , after which the valves for the intake j and port j^5 will close, it being understood that by the time the valves just mentioned close the piston in the cylinder J 90 will have nearly completed its stroke in the 95 direction of the arrow y . The valved intake j and the port j^5 are closed shortly before the piston in the cylinder J reaches the limit of its stroke in the direction of the arrow y , which will cause a partial vacuum to be 100 formed in the left-hand end of the cylinder J. As soon as the piston reaches the limit of its stroke in the direction of the arrow y the same series of operations will be repeated as the piston starts again in the direction of the 105 arrow z .

By referring to Fig. 1 it will be seen that the working piston, the piston for the cylinder J, and the pump-piston have a differential movement in relation to each other. 110

Having thus described my invention, what I claim, and desire to secure by Letters Patent, is—

1. An explosive-engine comprising a working cylinder and piston, a valved working-agent feed for both ends of the cylinder, automatically operated at predetermined times, a supplemental cylinder and piston, the latter being coupled with the working piston, the said second cylinder having inlets at each 115 end communicating with the working cylinder, mechanically-operated valves for said inlets, the second cylinder having outlets, a mechanically-operated valve for said outlets, and a pump joined with the outlets of the 120 second cylinder, for the purposes specified.

2. In an explosive-engine as described; a working cylinder and piston, valved intakes at each end of said working cylinder, centrally-arranged exhausts for said working 125 cylinder, a second cylinder and piston disposed below said working cylinder, said second piston being co-operatively joined with the said working piston, valved intakes at

each end of said working piston having connection with the exhausts of the working piston, valved exhausts for said second cylinder, a pump connected to said exhausts, said pump having a piston co-operatively joined to said working piston, and a governor-valve connected to the intake of the working cylinder, all being arranged substantially as shown and described.

10 3. A gas-engine, comprising a working cylinder and piston, said cylinder having a valved fuel-intake at each end, and a pair of centrally-disposed exhausts, a governor for controlling the fuel-feed to the said intakes, a second cylinder, and piston therefor, said second cylinder having an intake at each end, each intake having a mechanically-controlled valve, the said intakes having a crossed connection with the exhausts of the working cylinder, and the said second cylinder also having a mechanically-shifted valve-controlled offtake at each end, and a pump connected with the said offtakes, substantially as shown and for the purposes described.

25 4. An explosive-engine, comprising a working cylinder and a piston, automatically-operated means for feeding the working agent alternately into the opposite ends of the working cylinder, the said cylinder having a pair 30 of piston-controlled exhausts, a second cylinder and piston connected with the working cylinder and piston, the exhausts of the latter discharging through mechanically-controlled inlets, one on each end of the second cylinder, the exhaust of one end of the working cylinder being joined to the opposite end of the second cylinder, the exhaust of the other end of the working cylinder joining with the other end of the second cylinder, 35 and means for first drawing off the exploded charge from the working cylinder, and leading it back of the piston in the second cylinder, and then creating a vacuum at the rear of the two pistons and drawing in a new charge into the working cylinder, as set forth.

50 5. In an engine as described, a working cylinder and piston, a supplemental cylinder and piston, a crank-shaft, a cross-head connected with the working piston, a double crank-lever pivoted on the cross-head, the second cylinder-piston, having its rod pivot-

ally connected to one arm of the bell-crank lever, a pump having its piston-rod connected to the opposite arm of the said bell-crank lever, means for automatically feeding a working charge alternately into the opposite ends of the working cylinder, and means for leading the exploded charge from the working cylinder into the second cylinder back of its piston at predetermined times, an offtake in each end of the second cylinder for communicating with the pump, and mechanically-operated valves for the said latter offtakes, for the purposes specified.

65 6. In an engine as described, a working cylinder-piston, a supplemental cylinder and piston connected with the working cylinder and piston, and adapted to operate in harmony therewith, automatically-operated means for controlling the fuel-feed to the working cylinder, a means for leading the exploded charge from the working cylinder into the second cylinder at predetermined times, a pump having a suction-pipe, provided with valved laterals, one for each end of the second cylinder, and a condenser through which the said suction-pipe passes, for the purposes specified.

70 7. The combination with the cylinder A, 80 having valved intakes $a a'$, one at each end, and centrally-disposed exhausts $b b'$, the piston R, the cross-head C, connected with the piston R, the cylinder J, having inlets $j j'$, and outlets $j^5 j^6$, mechanically controlled for 85 each of the said inlets and outlets, the cross-pipes j^3 for joining the exhausts $b b'$ and the inlets $j j'$, the piston in cylinder J, the pump O, and the piston O' therefor, the condenser M, the offtake-pipe that joins the pump and 90 the offtakes from the cylinder J, said pipe being held to pass through the condenser, the crank-shaft, the lever F, connected to the crank-disk and pivotally joined to the cross-head, said lever having oppositely-extending 95 arms $f' f^2$, one of which f' pivotally joins with the pump-piston, and the other f^2 pivotally connects with the piston of cylinder J, all being arranged substantially as shown and described.
